UNITED STATES PATENT OFFICE.

EMANUEL EISENTRAUN, OF ODESSA, MISSOURI.

FRUIT-CAN FORMING AND SOLDERING MACHINE.

SPECIFICATION forming part of Letters Patent No. 514,453, dated February 13, 1894.

Application filed February 23, 1893. Serial No. 463,370. (No model.)

To all whom it may concern:

Be it known that I, EMANUEL EISENTRAUN, of Odessa, Lafayette county, Missouri, have invented certain new and useful Improvements in Fruit-Can Forming and Soldering Machines, of which the following is a full, clear, and exact description, reference being had to the accompanying drawings, forming a part hereof.

10 My invention relates to machines for forming and spreading the sides of sheet-metal fruit-cans and more particularly to securing the bottoms and top-rims to the sides of such cans.

15 The objects of my invention are to produce a can making machine, which shall be simple, strong, durable and inexpensive in construction, and rapid and effective in its operation and which shall be capable of use in 20 making fruit cans more rapidly than heretofore, and which shall, furthermore be easy and rapid to manipulate or operate.

To the above purposes, my invention consists in certain peculiar and novel features of 25 construction and arrangement as hereinafter described and claimed.

In order that my invention may be fully understood, I will proceed to describe it with reference to the accompanying drawings, in 30 which—

Figure 1 is a perspective view of a can-making machine embodying my invention; the can being shown in position in the machine so as to be operated upon thereby. Fig. 2 is 35 a vertical longitudinal section of the machine on the line 2—2 of Fig. 1. Fig. 3 is a view partly in side elevation and partly in transverse vertical section of the receiving and forming mechanism of the machine. Fig. 4 is 40 a detached perspective view of a portion of the spreading mechanism of the machine. Fig. 5 is an inner end elevation of the adjustable abutting disk of the forming mechanism. Fig. 6 is a detached view in end elevation of 45 certain of the operative parts of the spreading mechanism. Fig. 7 is a detached perspective view of the pivot head of the spreading mechanism. Fig. 8 is a horizontal section on the line 8—8 of Fig. 6. Fig. 9 is a detached 50 perspective view of one of the S-shaped spring spreader levers of the machine. Fig. 10 is a detached view in side elevation of the

retaining bolt for the spreader lever. Fig. 11, is a detail view of one of the adjustable retaining arms of the device.

55

In the said drawings, let 1 designate a portion of a bench or shelf or other similar support for sustaining the operative mechanism of the machine.

2 designates a U-shaped clamp bar, one end 60 of which is designed to rest upon the upper side of the support 1, and 3 designates a clamping screw-rod which works vertically through the opposite end of the clamp bar 2 and impinges at its upper end against the 65 under side of the support 1 so as to retain the clamp in its required position; this screw-rod having a suitable head or finger-piece 4 by which the rod is turned.

5 designates a pair of parallel bars or arms 70 which may be either of wood or metal as preferred and which are also of any suitable or preferred length. Through the rear ends of these bars or arms 5 extends a cross-bolt 6 which also extends transversely through a 75 lug or ear 7 which is formed upon the lower end of the clamp bar 2; the arrangement being such that the bars or arms can be set at any desired angle from the clamp bar 2 and then secured in such position by screwing 80 home the usual retaining nut for the bolt 6.

8 designates a bar which is either of wood or metal and also of oblong rectangular form and of any suitable or preferred length. The rear end 9 of this bar 8 is reduced in width 85 and is interposed between the outer or front ends of the bars or arms just described; the retaining bolt 10 extending transversely through the outer ends of the bars or arms 5 and also transversely through the reduced 90 inner end of the bar 8 so as to pivotally connect the bar 8 to the bars 5. The outer ends of the arms or bars 5 are preferably beveled obliquely outward and downward, as shown, and the shoulders which are left by reducing 95 the end 9 of the bar 8 are correspondingly inclined; the arrangement being such that the bar 8 shall by the contact of each inclined shoulder with the inclined ends of the bars 5, be retained in longitudinal alignment with 100 said bars 5.

To the under side of the bar 8 at a point near the outer extremity of said bar is secured a vertical pendent standard section 11

which may also be either of wood or metal and of any suitable or preferred length. The lower end of this standard section 11 is bifurcated, or in other words, is formed with a longitudinal slot 12 which opens at the lower end of the standard section, and which extends a suitable distance upward toward the upper end of said section, for a purpose to be presently explained.

13 designates a lower standard section which may also be either of wood or metal as preferred, and of any suitable or preferred length. At its lower end this lower standard section 13 rests upon the ground or upon the floor of the apartment in which the machine may be located, while transversely through the upper end of this lower standard section extends two horizontal bolts 14; these bolts 14 extend also through the longitudinal slot 12 just described, and carry at their outer ends retaining nuts 15; suitable washers 16 being interposed between the nuts 15 and the front side of the standard section 11. The arrangement is such that the lower standard section 13 may be moved longitudinally against the upper standard section 11 so as to lengthen or shorten the standard as required; the retaining nuts 15 being subsequently screwed home so as to retain the parts of the standards in their required position of adjustment.

17 designates a foot-lever or treadle, which may also be of wood or metal and which projects outward from the lower end of the lower standard section 13; the rear end of this treadle being forked or bifurcated so as to embrace the lower end of the standard section 13 and being pivoted to said standard section as at 18. To the inner or rear part of this treadle 17 is connected the lower end of a chain or other suitable flexible connection 19, an eye 20 serving as the means for such connection, the said flexible connection extending upward and being attached by an S-hook 21, or an equivalent device to the lower end of the vertically movable rod 22 for a purpose to be hereinafter explained.

23 designates a U-shaped supporting bar, the middle of the lower horizontal portion of which is formed with a pendent tubular pivot 24; this pivot extending downward within a tubular sleeve 25 which is inserted vertically into the outer end of the supporting bar 8 above described. One arm 26 of the U-shaped bar 23 is bifurcated or forked at its upper end as at 27 while the opposite arm 28 of the bar 23 is likewise forked or bifurcated at its upper end as at 29. Between the arms or forks 27 is pivoted an abutting disk 30; a transverse pivot pin 31 extending through a projection 32 at the outer side of this disk and also through the upper ends of the forked arms 27. A spiral contraction spring 33 is connected at its lower ends to the supporting bar 23 near the points of the union of such bar with the arm 26 and the upper end of this spring is connected to a clamp or ring

34, which surrounds a stud 35 which extends outwardly from the projection 32 of the disk 30. The arrangement is such that the contraction of the spring 33 tends to throw the disk or head 30 upward into oblique position, as shown in Fig. 3. The inner face of this disk 30 is formed with three radial grooves 36, the inner ends of which merge together at the center of the disk, and the outward ends of which open at the margin of said disk. Within each of these radial grooves 36 is placed an adjustable retaining arm 37, there being thus three of said arms. Each of these arms is of skeleton form and also of approximately U shape, the two arms constituting the body portion of the device extending parallel with each other and being united together at their outer ends by a hook 38 which is formed integrally with the arms 37 and which extends obliquely upward and inward toward the center of the disk. Three retaining screws 39 are inserted into the inner side of the disk 30, each of said screws being located about midway of the length of one of the grooves 36 and the head of each of said screws overlying the arms 37. The arrangement is such that by adjusting the arms 37 nearer to or farther from the center of the disk 30, and then tightening the screws 39, the arms may be retained in such position of adjustment for a purpose to be hereinafter explained.

Between the forked arms 29 of the supporting bar 23 is pivoted a circular trunnion piece 40, two studs or trunnions 41 extending oppositely outward from said trunnion ring enter pivotally into the upper ends of the forked arms 29. Through this trunnion ring 40 extends a rod or stem 42, the outer end of which extends between the two arms 43 of a fork which is pivoted as at 44 upon the lower end of the arm 28 at a point near its point of union with the arm 23. The lower portion of this fork extends horizontally above the bar 23 as shown and through its lower end extends loosely the vertical bolt or rod 22 above referred to, the head of this bolt or rod 22 resting upon the upper side of the arm 43. The inner end of the rod 42 is externally screw-threaded to enter an internally screw-threaded socket 45 of the disk-shaped head 46, as is clearly shown in Fig. 2. Upon this screw-threaded end of the rod 42 at a point some distance nearer its outer end, is screwed a collar 47 which is also of disk form; the rod 42 extending through an internally screw-threaded opening 48 at the center of the collar 47. This collar 47 is also formed with five or any other suitable or preferred number of radial recesses 49 which open at their outer ends at the margin of the collar or disk 47. From each of these recesses 49 extends laterally two sockets 50 which open only at one side of the disk or collar and into the recesses 49 is inserted the inner end of one of five S-shaped spreader-levers 51. The inner end of each of these levers is formed with two oppositely disposed

outwardly extending studs 52 which work within the cavities 50, and the outer end of each of these levers 51 is formed also with two oppositely disposed oppositely extending studs 53 which are pivotally connected to two oppositely disposed inwardly extending ears 54 upon each of five spreader plates 55 to be hereinafter more fully explained. The inner ends of these levers 51 are retained within the recesses 49 by a plate 56. This plate corresponding in size and shape to the collar or head 47 and having a number of radial recesses 57 opening out at the margin of the plate and registering with the recesses 49 of the head 47. Upon its inner side the plate 56 is formed with a stud 58 which enters a cavity 59 in the outer side of the head 47; the arrangement being such that the stud 58 prevents the plate 56 from rotating independently of the head 47.

60 designates a companion disk or head to the disk or head 30 above referred to. The rod 42 extends centrally through this head 60 in such manner that the head 60 can freely move longitudinally upon the rod. At its outer side the head 60 is formed centrally with an outwardly extending boss 61 through which the rod 42 also extends and this boss is prolonged outwardly in the form of a sleeve 62 which surrounds the rod 42 and extends outward toward the outer end of the same. The outer end of the sleeve 62 passes loosely through the trunnion-ring 40 and projects outwardly therefrom for a suitable distance, and a spiral expansion spring 64 surrounds the sleeve 62, and bears at its opposite ends against the boss 61 and said trunnion-ring; the tendency of this spring being to force and hold the clamping head or disk 60 to its inward position. A second spiral spring 65 surrounds the outer end portion of the rod 42 and is interposed between the outer end of the sleeve 62 and a ring 66 which loosely surrounds the rod 42 at the outer portion thereof. This spring 65 serves to force the ring 66 against the upper ends of the fork 43, for a purpose to be presently explained. Upon its inner side near the outer margin thereof the head 60 carries a number of adjustable U-shaped supports 67, there being three of such supports shown. The inner side of the head 60 is formed with three radial grooves 68, the inner ends of which merge into each other and which open at the margin of the head 60. Each support 67 is located within one of these grooves 68 and is adjustable longitudinally therein, and is also secured in any position of longitudinal adjustment by a screw 69 which is inserted into the groove 68 at a point about mid-way of the length thereof; the head of the screw overlying the arms of the support 67 and the purpose of these supports 67 being hereinafter described. From the inner side of the head 60 projects horizontally a short tubular portion 70 against the inner side of which rests the outer sides of the spreaders 55 above referred to. The spreaders 55, are

of segmental form, in cross-section, as shown, so as to conform to the inner curvature of the can, being formed.

The operation of the above described machine is as follows; when it is desired to form and solder a can, the heads 60 and 30 are first moved upward into inclined position, as shown in Fig. 3. The usual rim to which the top of the can is to be soldered is caused to surround the outer end of the adjustable supporting arms 67. The side portion 80 is now placed around the spreader plates 55, while the bottom of the can is now placed upon the end portion of the can at the same time bringing the whole can down between the two disks 30 and 60 in parallel position in Fig. 1. The operator now depresses the treadle 17 pulling down upon the flexible connection 19 and rod 22 and depressing the lower end of the fork 43; the upper ends of said fork simultaneously moving inward. As the upper ends of this fork thus move inward they come into contact with the ring 66 compressing the spring 65 and forcing the disk 46 inward and extending the levers 51 outward. This causes the spreaders 55 to press outward upon the inner surface of the side 80 of the can so as to cause such to assume a perfectly cylindrical form to be closely pressed against the outer margins of the bottom and rim of the can. Solder is applied along the longitudinal seam of the side 80. After this has been done, the pressure upon the treadle 17 is removed, and the spring 65 exerting its pressure against the collar 66, causes the rod or stem to move outward, and this movement retracts the spreaders, the arms thereof fulcruming against the inner margin of the tubular portion 70 of the disk or clamping-head 60. This outward movement of the rod or stem does not affect the position of the clamping-head or disk 60, the spring 64 holding said head inward with a yielding pressure. By grasping the can it may now be axially and slowly turned between the clamping-heads or disks while the solder is being applied to secure the bottom rim and head rim to the ends of the can. After this operation is completed, the head is pushed outward and the parts tilted up into the position shown in Fig. 3; the finished can being removed and the subsequent operations being repetitions of the one just described.

From the above description, it will be seen that I have produced a can making machine, which is simple, strong, durable, and inexpensive in construction and rapid and effective in its operation which is easily manipulated and capable of use in the formation of a great variety of fruit cans.

Having thus described my invention, what I claim as new therein, and desire to secure by Letters Patent, is—

1. A can forming and soldering machine, comprising a suitable framework, a bar carried by said framework, and a disk or clamping-head pivotally carried by said bar, and a spring-actuated disk or clamping head also

pivots carried by said bar, substantially as set forth.

2. A can forming and soldering machine, comprising a suitable framework, a bar carried by said framework, and a disk or clamping head carried by said bar, and a second disk or clamping-head supported from said bar, a lever pivotally carried by said bar, a spring-retracted rod or stem passing through the last-mentioned disk or clamping-head, and means to actuate the lever to overcome the resistance of the spring and move the rod or stem inward, substantially as set forth.

3. In a can forming and soldering machine, the combination with a framework, a bar carried by said framework, and a pair of clamping heads or disks carried by said bar, and means to adjust one of said disks toward the other, of a series of adjustable arms carried at the inner sides of said clamping heads or disks, and having hooked outer ends adapted to receive the ends of the can, and means to secure said arms at any desired adjustment, substantially as set forth.

4. A can forming and soldering machine, comprising a suitable framework, a U-shaped supporting bar pivotally mounted upon said framework, and clamping-heads pivotally carried by said bar, a lever pivoted to the U-shaped bar, a spring retracted rod or stem passing through one of said clamping heads or disks, a disk shaped head upon the inner end of the rod or stem, and a collar mounted upon the rod or stem near its outer end, and means to actuate the lever so that it shall contact with the collar and move the rod or stem inward, substantially as set forth.

5. A can forming and soldering machine, comprising a framework, a U-shaped bar pivotally mounted thereon, a pair of clamping heads or disks pivotally supported by said U-shaped bar, a spring-retracted rod or stem passing centrally through and carried by one of said clamping-heads, and a set of spreader arms pivotally carried by said rod or stem, and a corresponding set of spreader-plates carried by said spreader-arms, a collar upon the outer end of said rod or stem, a forked-lever pivoted to the U-shaped bar and fitting upon opposite sides of the said rod or stem, a treadle, and a rod and chain connecting said treadle to the inner end of the forked-lever, substantially as set forth.

6. A fruit can forming and soldering machine, comprising a framework, a U-shaped bar having its upper ends forked, and pivotally mounted upon the framework, clamping heads or disks pivotally supported by said U-shaped bar, a forked-lever pivoted to the U-shaped bar, a horizontal rod or stem projecting at one end between the forked arms of the lever, and passing centrally through one of the clamping-heads, a disk-head secured upon the inner end of said rod or stem, and a collar also carried by said rod or stem outward from the disk-head, a set of spreader arms pivoted to and extending radially from

the said collar, and a corresponding set of spreader-plates pivotally connected to said spreader arms, and means to move the rod inward to spread said plates, and means to automatically move the said rod outward to retract said plates, substantially as set forth.

7. In a fruit can forming and soldering machine, a framework, a supporting U-shaped bar pivotally arranged above said framework, a clamping-head pivotally supported by said U-shaped bar, a forked-lever pivoted to said supporting bar, a treadle or foot-lever operatively connected to said lever bar, a horizontal and transversely extending stem or rod projecting at one end between the forked arms of the pivoted bar, and a disk-head secured upon the opposite end, a collar secured upon said stem, a set of spreader arms extending pivotally and radially from said collar, a corresponding set of spreader plates pivotally secured to said spreader arms, a sliding disk or clamping-head, a boss and sleeve secured to said disk or head and surrounding said stem or rod, a ring or collar secured on the stem or rod near its outer end, and a trunnion-ring loosely surrounding said sleeve and pivotally arranged in the bifurcated end of one of the vertical arms of the supporting bar, a spring surrounding said sleeve and bearing at its opposite ends against the said boss and the pivotally arranged trunnion-ring, and a spring surrounding said stem or rod and bearing at its opposite ends against the outer end of the sleeve and the ring or collar, substantially as described.

8. In a fruit can forming and soldering machine, a framework, a supporting bar pivotally arranged on said framework, a forked-lever pivoted to said supporting bar, a horizontal and transversely extending stem or rod, a disk-head, a collar provided with a set of spreader arms, a corresponding set of spreader plates pivoted to said spreader arms, a disk or clamping-head, a tubular portion secured to said disk or clamping-head on its inner side, a boss and a sleeve projecting from the outer side of said disk or clamping-head, a spring surrounding said sleeve, a ring or collar, and a spring bearing against said ring or collar all carried by said stem or rod, in combination with a disk or head pivotally arranged between the bifurcated or forked arms of the opposite vertical arm of the supporting bar, substantially as described.

9. A fruit-can forming and soldering machine, comprising a suitable framework, a supporting U-shaped bar pivotally mounted thereon, a clamping-head or disk pivotally carried by the U-shaped bar, and an adjustable and spring-actuated clamping-head or disk also pivotally supported by the U-shaped bar, and a contraction-spring, connecting the first-mentioned clamping-head to the lower portion of the U-shaped bar, substantially as and for the purpose set forth.

10. In a fruit can forming and soldering machine, a framework comprising a vertically

erected and extensible standard, a foot-lever or treadle pivoted at the lower end thereof, a horizontally extending bar secured upon the upper end of said extensible standard, a pair of parallel arms pivotally connected to said horizontal bar, a clamping bar pivoted between the outer ends of said parallel bars and a clamping screw for securing said clamping bar to a bench or table, a U-shaped bar piv-

otally supported upon the horizontal bar, and clamping heads carried by said U-shaped bar, substantially as described.

In testimony whereof I affix my signature in the presence of two witnesses.

EMANUEL EISENTRAUN.
